CLAIM

The ornamental design for a heat sink module, as shown and described.

DESCRIPTION

FIG. 1 is top perspective view of a heat sink module; FIG. 2 is a bottom perspective view of the heat sink module of FIG. 1; FIG. 3 is a top view of the heat sink module of FIG. 1; FIG. 4 is a bottom view of the heat sink module of FIG. 1; FIG. 5 is a front view of the heat sink module of FIG. 1; FIG. 6 is a rear view of the heat sink module of FIG. 1; FIG. 7 is a left side view of the heat sink module of FIG. 1; and, FIG. 8 is a right side view of the heat sink module of FIG. 1.

The broken lines shown in the drawings illustrate portions of the heat sink module and form no part of the claimed design.

1 Claim, 4 Drawing Sheets
